UNITED STATES PATENT OFFICE.

CARL SCRABIC, OF URBANA, OHIO.

STYLUS MOUNTING FOR SOUND BOXES.

Application filed March 28, 1921. Serial No. 456,048.

This invention relates broadly to sound reproducing machines, and has particular reference to the sound box structures thereof, the primary object of the invention being to provide a sound box with an improved mounting for effecting the oscillatory support of a cooperative stylus bar, whereby said stylus bar will be properly maintained in engagement with the diaphragm of the sound box in order that the vibratory movements, imparted to the stylus bar through engagement with record grooves, will be properly and faithfully transmitted to the diaphragm so as to cause the latter to vibrate properly and in accordance with the sound undulations physically provided in the grooves of a record.

In carrying out the invention there is employed a sound box which includes a casing having a vibratable diaphragm mounted therein, the lower portion of the casing being provided with a pair of spaced brackets between which a stylus bar is movably trunnioned, the said stylus bar having its upper end positively connected with the central portion of the diaphragm, while the lower end of said bar, beneath the pivotal mounting thereof is formed to receive a record engaging needle, a crank projection being provided upon the stylus bar for cooperation with a casing carried stationarily mounted spring, the construction and position of the spring being such that by its engagement with the crank projection, the said stylus bar will tend to revolve about its pivotal mounting so that tension may be maintained between the upper end of said bar and the diaphragm, in order to render the latter susceptible to the slightest vibratory movements on the part of the stylus bar.

With these and other objects in view, as will appear as the description proceeds, the invention accordingly consists in the novel features of construction, combinations of elements and arrangements of parts, herein-after to be fully described and pointed out in the appended claims.

In the accompanying drawing, forming a part of the present disclosure:

50 Figure 1 is a vertical sectional view taken through a sound box and illustrating the application thereto of the improved stylus bar mounting comprising the present invention,

Figure 2 is a side elevation, and

55 Figure 3 is a horizontal sectional view

taken on the plane disclosed by the line 3—3 of Figure 2.

In the accompanying drawing the numeral 1 designates generally a sound box or reproducer of the type utilized in connection with talking machines, the same being adapted to be suitably carried by the outer end of a tone arm 2 and adapted as usual for cooperation with a rotatably carried record, not shown, for the purpose of reproducing the sound undulations imposed on said record. In this instance the sound box includes a casing 3 having a diaphragm chamber 4 provided therein, the said chamber being adapted for the reception of a vibratable diaphragm 5, the said diaphragm is adapted for cooperation with the stylus bar 6, which is pivotally mounted as at 7 in connection with the casing and is adapted to be oscillated, in the usual manner, by cooperation with the record grooves and to transmit the vibratory movement thereof to the diaphragm.

The present invention concerns itself more particularly in providing an improved mounting for the stylus bar, in order that the latter may be caused to vibrate properly, to respond to the most minute undulations of a record groove and to cooperate with the diaphragm in such manner that the latter will be enabled to reproduce fine tonal shades which are frequently lost in sound reproduction by reason of improperly mounted stylus bars.

To this end, the casing 3 has its annular outer wall provided, contiguous to its lower portion, with a recess 8, in which is seated a bracket or plate 9, the latter being formed to include at its outer edges a pair of forwardly extending spaced arms 10, between which the stylus bar 6 is mounted. The outer ends of the arms 10 are relatively enlarged and are provided with horizontally extending, registering threaded openings 11, in which are carried threaded bearing screws 12, of suitably hardened steel. These screws have their inner ends formed with conical sockets 13, which are adapted to receive the sharp pointed outer ends of a pivot pin 14. This pin passes horizontally through the enlarged lower end 15 of the stylus bar 6, and is suitably fixed to said stylus bar in order to move in unison therewith. It will be seen that by properly adjusting the screws 12, proper pressure may

be brought to bear upon the ends of the pin 14, thus providing an efficient construction for producing a trunnioned support for the stylus bar, and which support will be of such character as to permit the stylus bar to oscillate or vibrate freely, in a manner which will be characterized by an absence of all undue friction. Furthermore, the adjustment of the bearing screws 12 may be maintained by providing the outer ends of the same with lock nuts 16, which operate to engage with the sides of the arms 10 and to prevent loss of adjustment on the part of said screws. The lower end 15 of the stylus bar is also formed with the usual needle socket 17, in which a needle 18 may be removably positioned or retained in said socket by means of a set screw 19. The stylus bar, above the portion 15 terminates in a relatively reduced upwardly tapering extremity 20, which in turn is abruptly terminated in an inwardly directed angularly disposed diaphragm engaging portion 21. This portion extends longitudinally of the axis of said casing and is terminated in physical contact with the outer wall of the diaphragm, a screw or the like 22 being adapted to positively connect the diaphragm for movement in unison with the upper reduced end of the stylus bar.

In order to insure proper vibration of the diaphragm in unison and harmony with the sensitively mounted stylus bar, the latter is provided, at a point adjacent to its pivotal support, with an inwardly extending, integral crank projection 23, which is disposed to occupy a portion of the space between the arms 10. Cooperative with this projection 23 is a leaf spring 24, which is carried, in this instance, to be connected with and to lie immediately below the plate 9, the said spring including a vertically disposed inwardly located finger 25 normally situated to contact with the under surface of the plate 9. The finger 25 terminates in a forwardly directed, longitudinally extending portion 26 which, in turn, terminates in a hooked finger 27, the latter being adapted to contact and to be maintained constantly in engagement with the under surface of the projection 23. This feature is insured by the provision of a screw 28, which passes through an opening provided in a bend 29 provided intermediately in the portion 26 of the spring 24, the inner end of the screw being threaded into an opening provided therefor in the plate 9 or its equivalent. Manifestly, by tightening the screw 28 into frictional engagement with the bend 29 of the spring, the finger 27 will be positively forced into engagement with the projection 23 so as to exercise resilient pressure upon such projection. This results, therefore, in applying such pressure to the stylus bar that the upper end of the latter will tend

normally to swing outwardly and to thereby result in placing a tension on the connection between the upper end of said stylus bar and the diaphragm. This tension may be regulated but is sufficient to cause the diaphragm to oscillate in precise conformity with the upper end of the stylus bar.

From the foregoing description it will be apparent that the present invention provides a practical, simple and efficient mounting for insuring accurate and proper vibration of the stylus bar of a sound box and to properly transmit the oscillation of said stylus bar to an associated diaphragm. The construction of the mounting by reason of its simplicity will be reliable and effective, and adjustments, if required, may be readily effected. The construction is such as to admit of economical manufacture and at the same time to permit of improved sound reproduction over the ordinary standard constructions now commonly employed.

What is claimed is:

1. In a sound box, a casing, a stylus bar pivotally connected to the casing for movement about an axis disposed perpendicularly to the major and longitudinal axis of the stylus bar, said stylus bar being formed with a horizontally disposed projection extending from the stylus contiguous to its pivotal mounting and facing toward said casing, a substantially U shaped leaf spring having the opposite arm portions thereof arranged to engage respectively said casing and said projection, and a tensioning element passing through the intermediate portion of said spring and connecting the latter with said casing, one end of said spring engaging the under surface of said projection in order to produce a force tending to swing the upper end of the stylus bar in a direction away from said casing.

2. In a sound box, a casing, a diaphragm mounted within said casing, a stylus bar pivotally connected to the lower portion of the casing and having the upper end thereof connected to the central portion of the diaphragm, a short offset crank projection extending rigidly and horizontally from said stylus bar in substantially the plane of the pivotal mounting thereof and facing toward said casing, a leaf spring of substantially U shaped configuration including free outer arms, one of said arms engaging the under surface of said projection to produce a pressure thereon tending to swing the upper end of said stylus bar in a direction away from the casing, and a threaded adjustable tensioning member connected with the intermediate portion of said spring and said casing for controlling the degree of pressure exercised by said spring on said stylus bar.

In testimony whereof I affix my signature.

CARL SCRABIC.
